UNITED STATES PATENT OFFICE.

JOHN D. PEDERSEN, OF JACKSON, WYOMING.

FIREARM.

1,023,169.

Specification of Letters Patent.

Patented Apr. 16, 1912.

Application filed May 5, 1910. Serial No. 559,546.

To all whom it may concern:

Be it known that I, JOHN D. PEDERSEN, a citizen of the United States, residing at Jackson, county of Uinta, and State of Wyoming, have invented certain new and useful Improvements in Firearms, of which the following is a full, clear, and exact description.

The object of my present invention is to 10 improve in certain particulars upon the fire arms such as are described, for example, in Letters Patent granted to me on January 5th, 1909, No. 908,883; the particular points to which my present invention is directed 15 being to provide means in a magazine fire arm for raising the rear end of the rear cartridge in the magazine at the initiation of the feeding operation and immediately thereafter interposing means to positively 20 stop the second cartridge from partaking of the extreme rearward movement of the action bar; further, to provide means whereby the rear cartridge shall be held in substantially perfect alinement in the magazine 25 during the operation of charging the magazine; to hold down the bullet end of the rear cartridge while its rim is being raised at the initiation of the feeding operation, so that the cartridge will be presented in proper 30 alinement to the breech-block; a further object of my invention is to provide means that will insure the proper return of a cartridge to the magazine in the event that the cartridge feeding operation is so incomplete 35 that the cartridge is not delivered to the breech-block and thence to the barrel of the fire arm; other objects will appear in the following explanation.

In the annexed drawings—Figure 1 is a 40 longitudinal section of the operating parts of a rifle showing the position of the parts just after firing. Fig. 2 is a similar section after the discharged shell has been ejected and the breech-block and action bar are near 45 their rearward limit of travel. Fig. 3 is a top plan view of the action bar. Fig. 4 is an elevation of the rearward part of the same. Fig. 5 is a cross section on the line V—V of Fig. 4, and Fig. 6 shows in perspective the retainer.

In the form of rifle which I have chosen 50 to illustrate my invention the magazine A is moved with the handle or fore-arm B, and is provided with a spring-pressed plunger 55 C. The barrel D is screwed into the frame or receiver E, which serves both to connect

the barrel with the stock F and to inclose the breech-block, hammer and cartridge feeding mechanism. The rear end of the magazine A is formed into an action bar G 60 which, as the handle B is moved rearwardly, engages, as by notch H, with the tooth or projection I of the breech-block J so as to move the latter rearwardly and in its motion to cock the hammer K, as shown in Fig. 2. 65 The action bar G is provided with a longitudinal slot G' extending forwardly from its rear end, said slot being rectangular in cross section, and also with a circular slot, in which is loosely mounted a cartridge stop 70 L which is free to slide back and forth in its slot. The forward portion of guard R has a slot R', into which the cartridge stop L projects. This slot R' allows the stop L a limited reciprocal movement. Projecting 75 laterally into the longitudinal slot G' is a spring-pressed dog G², whose function is to elevate the cartridge carrier M. This function is performed as the parts move forward from the rearward position shown in Fig. 2 to the closed, or forward, position illustrated in Fig. 1, the parts being so arranged that, as the action bar moves rearward, the cartridge carrier enters the slot G' and the dog G² passes over the 80 face of the cartridge carrier M until it reaches the cam-grove M' into which it enters under the pressure of the spring G². As the action bar is moved forward by the handle B, the dog G², riding in the groove M', 85 raises the cartridge carrier so as to raise the cartridge, as M², and forces it into the groove J² on the front face of breech-block J. 90

Fixed between the barrel D and the magazine A is what I term a retainer N. This 95 may be provided with a recess N' upon its upper face to fit over a corresponding shoulder in the forward part of the receiver E, or be provided with other means to hold it in fixed longitudinal and lateral position 100 while the magazine is reciprocated. The retainer, as shown in Figs. 1, 2 and 6, is preferably formed with a forwardly projecting tongue N⁴ lying between the barrel and the magazine but not occupying all the 105 vertical space between them, and its rearward end projects into the chamber O of the receiver, being formed with a beveled nose N³, and a groove or recess N² on its under face.

The functions of the retainer N and the cartridge stop L are, generally speaking, ex- 110

ercised as follows: In fire arms of this description the lengths of the cartridges used vary. For example, in 22 caliber rifles "long" and "short" 22 cartridges—differing from each other by a quarter of an inch or more in length—are frequently loaded into the magazine indiscriminately. If the parts, and particularly the cartridge carrier, be adjusted nicely for the longer cartridges, the shorter ones may be twisted by the too abrupt elevation of their rear ends just as they are being caught by the cartridge carrier on their way from the magazine to the barrel. Another difficulty often experienced is that a second cartridge is forced rearwardly in the act of loading and becomes lodged in the chamber O of the receiver, causing trouble or danger. Still another danger arises out of the necessarily rapid action of the parts in the ordinary act of loading, if the bullet end of the rearmost cartridge is in immediate contact with the firing end or rim of the next one at the instant that the rim of the rear cartridge is thrown—necessarily with considerable force—against the breech-block J, in which condition of things there is danger of premature explosion of the second cartridge. Still another trouble is experienced when, owing to incomplete or imperfect actuation of the parts, the rearmost cartridge is not moved upward into the breech-block groove J', and, on the forward reciprocation of the handle G, the cartridge, being carried forward and not being in proper alinement, is jammed at the mouth of the magazine. In the use of my invention, however, these troubles, and others interfering with rapid and smooth action of the parts in practical use, are entirely avoided. As will be observed in Fig. 1, the rearmost cartridge in the magazine, being at the rear of the magazine proper, is held between the action-bar and the retainer N, which projects so far to the rear as to prevent the cartridge, whether long or short, from being crossed as it is fed back to the cartridge carrier M. As this feeding takes place it is elevated over the inclined upper and forward face L' of the cartridge stop L, and so reaches the carrier M in proper position; as the rear cartridge is so delivered, the next cartridge is carried rearward by the action-bar until the cartridge stop L is arrested by the rear end of slot R', when that cartridge is arrested, in the position shown in Fig. 2, out of contact with the rear cartridge, which in the forward reciprocation of the handle B is carried up and inserted in the rifle barrel, the second cartridge being then moved to the rear end of the action-bar by the tension of the magazine spring, to position shown by Fig. 1, ready for the next operation. Taking the condition of things shown in Fig. 2, and assuming that the operation

of loading is unsuccessful because the carrier dog G' has not been moved rearward far enough to snap into carrier slot M', it is clear that the forward reciprocation of the handle B will carry the rear cartridge forward with the magazine A. If suitable provision be not made, the cartridge, particularly at its rim, may be caught or jammed between the cartridge stop L and the rear end of the retainer as the cartridge rides downward from elevated to normal position; but with my invention, the cartridge rim will slip past the beveled nose N', into groove N'', which allows cartridge stop L to move freely to its forward position. The thin tongue N' of the retainer is merely to hold the said retainer in place especially when the action bar is in its forward position. (See Fig. 1.) The tongue N' bearing against the under side of barrel D while the mid-portion of retainer bears on its lower side, against the top of the action bar the rear end of retainer is prevented from dropping downwardly and thereby disengaging the retainer from its engagement with the receiver. This engagement is by means of the recess N' in the top of the retainer.

From the foregoing my invention will be readily understood. It may be varied in many particulars and may be applied to other uses than those illustrated and described.

What I claim as my invention is:

1. The combination in a fire arm, of a reciprocating tubular action bar having at the rear an outlet opening for cartridges transverse to the length of said bar, a cartridge stop with reference to which the magazine reciprocates and arranged to deflect the rearmost cartridge into the outlet opening when the same is passing the cartridge stop, and a retainer forward from the cartridge stop to prevent the upward turning of the cartridge as the same enters the receiver, said retainer having a recess in the lower portion thereof adapted to receive the rim of a cartridge and allow said cartridge-stop to pass said rim from the rear to the front side thereof.

2. In a fire arm, a reciprocating action bar, a cartridge stop, in combination with a retainer located above the action bar and projecting into the receiver, said retainer having a recess in the lower side thereof adapted to receive the rim of the cartridge and allow the cartridge stop to pass the said rim from the rear to the front side thereof, and means for holding said retainer in position.

3. In a fire arm, a reciprocating action bar, a cartridge stop, in combination with a retainer having a beveled nose N', a recess N' on the upper portion thereof adapted to fit a shoulder on the receiver, a recess in the

lower portion thereof between the nose N³ and recess N' adapted to receive the rim of the cartridge and thereby allow the cartridge stop to pass the said rim from the 5 rear to the front side thereof and means for holding the same in position.

4. In a fire arm, a retainer having a beveled nose N³, a groove N² adapted to receive the rim of a cartridge, a forwardly projecting tongue N⁴, and a recess N' between the groove N² and tongue N⁴ and adapted to engage over a shoulder to hold the same in place.
5. In a fire arm, a retainer having at one

end a projecting nose, the other end thereof 15 adapted to be engaged to secure the said retainer firmly in the fire arm, said retainer having a recess N² in the lower side thereof between said ends to receive the rim of a cartridge.
